UNITED STATES PATENT OFFICE.

JESSE BELTON BOWEN, OF LUMBERTON, NORTH CAROLINA.

PROPELLED DEVICE FOR TYPE-WRITER CARRIAGES.

1,165,150.

Specification of Letters Patent.

Patented Dec. 21, 1915.

Application filed March 24, 1915. Serial No. 16,616.

To all whom it may concern:

Be it known that I, JESSE B. BOWEN, a citizen of the United States, and a resident of Lumberton, in the county of Robeson and State of North Carolina, have invented a certain new and useful Improvement in Propelling Devices for Type-Writer Carriages, of which the following is a specification.

My invention relates to improvements in propelling devices for typewriter carriages, and it consists in the combinations, constructions, and arrangements herein described and claimed.

An object of my invention is to provide a device by means of which the carriage may be placed under tension so as to move forwardly in the act of writing, but which may be instantly returned to its original position.

A further object of my invention is to provide a device of the type described in which the return of the carriage to its original position is effected by means of a spring or similar tension device, thereby returning the carriage always with the same velocity or speed.

A further object of my invention is to provide means for returning the carriage to its initial position which will prevent injury to the carriage due to the force with which it is ordinarily moved backward to its original position when an operator is trying to write rapidly.

A further object of my invention is to provide a novel form of carriage propelling means which is simple in construction and which will not easily get out of order.

Other objects and advantages will appear in the following specification, and the novel features of the invention will be particularly pointed out in the appended claims.

My invention is illustrated in the accompanying drawings forming part of this application, in which:

Figure 1 is a side view of the device as applied to a typewriter, Fig. 2 is a section along the line 2-2 of Fig. 1, and Fig. 3 is a detail plan view of a portion of the device.

In the following description I have referred only to the old parts of a typewriter that are necessary in a clear explanation of the operation of my invention, and in the drawings I have shown only such parts as tend to lend to an understanding of the invention.

The main frame of a typewriter is indi-

cated at 1. The frame is provided with the usual rail supports 2 bearing the rail 3 upon which the carriage frame 4 is mounted, wheels or rollers 5 being designed to run on the rail 3. Secured to the carriage frame 4 is an extension 6 bearing a rack 7. The latter is designed to engage a gear 8 mounted on a shaft 9 carried by a suitable support 10, said shaft 9 bearing a gear 11 arranged to mesh with an arc-shaped rack member 12, on one end of a bell crank lever 13. The latter is mounted on a fulcrum 14 carried by a bracket 15 secured to the frame 1. This bell crank lever 13 has a portion 13^a at right angles to the part bearing the rack 12, said portion 13^a being provided with a slot 13^b, see Fig. 2.

Referring now to Fig. 2, I have shown therein a key 16 which is mounted on a bell crank lever 17 pivoted at 18 to a part of the frame and held normally in an upright position by means of a spring 19. The opposite end of the bell crank lever 17 is slotted as shown at 17^a to receive the shaft 20 of a wheel or roller 21 which is designed to play in a slot 22^a of a lever 22 pivoted at 23. The opposite end of the lever 22 is provided with a slot 22^b arranged to receive a pin 24 carried by a rolling frame or carriage like that shown in Fig. 3. This carriage consists of a body portion 25 having an opening 25^a for the pin 24, and openings 26 for wheels 27 mounted on shafts 28. The wheels 27 run on the frame 13^a as shown in Fig. 2. The end of the pin 24 is connected by means of a wire or flexible member 29 with the spring 30, the opposite end of the spring being connected to the frame 1. A spring 31 connects the shaft 20 of the roller 21 with a portion 95 of the frame.

From the foregoing description of the various parts of the device, the operation thereof may be readily understood. Consider Fig. 1. The spring 30 exerts a tension on the pin 24 and hence on the carriage 25. This tension is communicated to the frame portion 13^a of the bell crank lever 13, so as to tend to swing the arc-shaped rack 12 in the direction indicated by the curved arrow. This tends to turn the gear 11 and also the gear 8 in the directions indicated by their respective arrows, so that the carriage tends to move from the left of Fig. 1 to the right. Now, when a key is depressed in the ordinary manner, the escapement mechanism (not shown, but which may be any

ordinary escapement mechanism) will permit the carriage to move. When the end of the line is reached, or when it is desired to return the carriage, the key 16 shown in Fig. 2 is depressed. This will move the wheel or roller 21 to the opposite end of the slot 22^a whereupon the spring 31 will cause the lever 22 to be rotated on its pivot thereby moving the carriage 25 to the opposite end of the frame 13^a. When this occurs, the tension on the spring 30, shown in Fig. 1, will of course be shifted to the opposite end of the bell crank lever. Since there is nothing to oppose the return of the carriage, it will be immediately carried back to its original position. On the release of the key 16, the tension of the spring 19 will cause the key to return to its original position and the action of the spring 31 will swing the lever 22 backwardly, thus moving the carriage 25 to its original position and placing the tension again on the lower end of the bell crank lever as shown in Fig. 1. Now on the operation of the keys, the carriage will move forward in a step-by-step movement which is of course governed by the escape mechanism not shown.

It will be readily seen that no matter how hard the key 16 may be depressed, the carriage will be returned with a force which is dependent upon the tension of the spring 30, so that instead of "slapping" the carriage back as so many operators do when they are writing rapidly, thereby injuring the carriage and the parts associated therewith, the carriage will be brought back quickly but with a constant velocity dependent upon the tension of the spring.

I claim:

1. The combination with a typewriter frame, of a carriage movable thereon, a rack carried by the carriage, a bell crank lever provided with an arc-shaped rack, gearing for transmitting the movement of the arc-shaped rack to the first mentioned rack, a spring, and means for shifting the tension of the spring from one portion of said bell crank lever to another, thereby shifting the direction of tension on the carriage.

2. The combination with a typewriter frame, and a carriage movable thereon, of means for placing said carriage under tension in two opposite directions, said means comprising a rack carried by said carriage, a bell crank lever having an arm provided with an arc-shaped rack, gearing connecting both said racks, a spring, and means including a member slidably associated with said bell crank lever for placing the tension of the spring at different portions of the

bell crank lever and thereby shifting the tension on the carriage.

3. The combination with a typewriter having a frame, and a carriage movable thereon, of means for placing the carriage under tension in one direction and in the opposite direction at will, said means comprising a rack mounted on said carriage, a T-shaped bell crank lever fulcrumed on said frame, a central arm on said bell crank lever being provided with an arc-shaped rack, gearing connecting said arc-shaped rack with said first mentioned rack, a member slidably associated with said bell crank lever and shiftable to either side of the fulcrum of the lever, and a spring connected with said shiftable member for exerting tension on the latter.

4. The combination with a typewriter having a frame, and a carriage movable thereon, of means for placing the carriage under tension in one direction and in the opposite direction at will, said means comprising a rack mounted on said carriage, a T-shaped bell crank lever fulcrumed on said frame, the central arm of said bell crank lever being provided with an arc-shaped rack, gearing connecting said arc-shaped rack with said first mentioned rack, a member slidably associated with said bell crank lever and slidable on either side of the fulcrum of the lever, a spring connected with said slidable member for exerting tension on the latter, and means for shifting said slidable member to the opposite sides of the fulcrum of said bell crank lever.

5. The combination with a typewriter having a frame, and a carriage movable thereon, of means for placing the carriage under tension in one direction and in the opposite direction at will, said means comprising a rack mounted on said carriage, a T-shaped bell crank lever fulcrumed on said frame, the central arm of said bell crank lever being provided with an arc-shaped rack, gearing connecting said arc-shaped rack with said first-mentioned rack, a member slidably associated with said bell crank lever and shiftable to either side of the fulcrum of the lever, a spring connected with said shiftable member for exerting tension on the latter, and means for shifting said shiftable member to the opposite sides of the fulcrum of said bell crank lever, said last named means comprising a key, and a lever operatively connected with said key.

JESSE BELTON BOWEN.
